UNITED STATES PATENT OFFICE.

ROBERT R. DUNLOP, OF COLUMBUS, OHIO, ASSIGNOR TO THE JEFFREY MANUFACTURING COMPANY, OF COLUMBUS, OHIO, A CORPORATION.

MINING-MACHINE

1,267,992.

Specification of Letters Patent. Patented May 28, 1918.

Application filed July 28, 1914, Serial No. 853,644. Renewed October 25, 1917. Serial No. 198,545.

To all whom it may concern:

Be it known that I, ROBERT R. DUNLOP, a citizen of the United States, residing at Columbus, in the county of Franklin and 5 State of Ohio, have invented certain new and useful Improvements in Mining-Machines, of which the following is a specification; reference being had therein to the accompanying drawing.

10 The present invention relates especially to mining machines of the class in which each is provided with its own track wheels and is adapted to perform the cutting operations while supported on the said track 15 wheels. A machine embodying my invention is adapted to travel into a mine room along a central track and, after reaching a suitable position, is adapted to cut a semi-circular kerf into the coal at the face of the 20 room.

It is often desirable to use such a machine in places where the full semicircular cut is undesirable, or where a longer face is required than can be made from the pivot 25 point. In such cases the cutting element must be fed into the coal by the bodily movement of the machine along the track, which, in such cases, is laid at a proper distance from the coal face to secure the 30 desired depth of cut. As the tractive effort of the propelling wheels is insufficient to accomplish such feeding, it has been customary to resort to anchors, fixed in, or near, the coal face, to which a feed cable is attached, 35 the winding up of which draws the machine along the track to cut the coal.

In earlier machines of the class to which this invention specifically relates a single feed cable was provided which was used 40 optionally either to swing the cutter mechanism with respect to the main frame or to move the whole machine bodily. This construction caused much loss of time when it was necessary to shift the cable from one 45 position to the other. And even when the cable was in position for feeding the machine bodily it could, without adjustment, move it in one direction only. If movement in the other direction was desired the cable 50 had to be moved to another position.

One of the objects of this invention is to provide a means supplemental to and independent of the cable which controls the movement of the cutter mechanism on the 55 frame, for moving the whole machine bodily

along the track. Another object is to provide means whereby the machine can be moved bodily along the track in either direction at the will of the operator and without the shifting of cables, anchor pins or 60 similar devices. Stated more specifically one of the objects of the invention is to provide a machine of this general class with a feeding mechanism adapted to engage a rack rail laid along the track. Other objects of 65 the invention will be apparent from the following specification and claims.

The device by which I attain these objects will be hereinafter fully set forth, reference being had to the accompanying drawings of 70 which—

Figure 1 is a general plan view of the machines.

Fig. 2 is a side elevation of the machine illustrated in Fig. 1.

Fig. 3 is a fragmentary plan view of the details of the rack rail traction device.

Fig. 4 is a diagrammatic plan view of the machine working on the long wall system of mining.

Figs. 5, 6, 7 and 8 are diagrammatic plan views of the machine in the several stages of operation in a narrow working place.

Fig. 9 is a fragmentary detail of the ratchet drive mechanism for the rack rail 85 sprocket wheel.

Like numerals refer to similar parts in the several figures.

As illustrated in the drawings this machine comprises a supporting truck, adapted 90 to travel over the tracks of the mine, upon which is mounted a coal cutting mechanism having a horizontally projecting cutter arm adapted to be rotated about a vertical axis. Mounted upon the truck platform are power 95 devices by which the truck wheels may be rotated to propel the machine along the mine tracks from one working place to another, and by which is actuated my improved positive traction device by which the 100 machine is driven along the track to force the cutter arm against the coal to cut it.

The truck consists of a structural steel platform 1 having suitable axle boxes in which are journaled the axles 2 and 3 to 105 which are fixed the track wheels 4 and 5 adapted to travel over the rails 6 of the mine tracks. Attached to the truck platform 1 are guide pedestals 7 which engage the depending lugs 8 of the supporting ring 9. 110

Mounted upon the supporting ring 9, adapted to rotation about the vertical axis thereof, is a main frame plate 10 of the coal cutting element, to which is attached the 5 horizontally projecting cutter arm 11 which is of a type well known in the art. Suitable means for effecting the vertical adjustment of the supporting ring 9 are contained in the pedestals 7, but as they form no part of 10 the present invention they need not be specifically described. Mounted on the frame plate 10 is a winding drum 12 upon which may be wound the feed cable 13, the outer end of which may be attached to projections 15 of the supporting ring to cause the rotation of the coal cutter thereon. A suitable motor 14 is attached to the frame plate 10 and is connected by suitable gearing to actuate the coal cutter and the winding drum.

20 Mounted on the truck platform 1, at the rear of the mechanism above described, is a motor 15 connected by suitable worm gearing to the cross shaft 16 to drive it. The shaft 16 is supported in bearings 17, 18 and 25 19 attached to the truck platform, and carries a sprocket wheel 20, connected thereto by a clutch 21. The sprocket wheel 20 serves, through the chain 22 and sprocket wheel 23, to drive the axle 2 and wheels 4 30 to propel the machine from place to place. Mounted upon the shaft 16 and connected thereto by a clutch 24 is an eccentric 25 by which my improved positive traction device is actuated, as will hereinafter appear.

35 Pivoted on the extended ends of the axle 2 are two arms 26 having at their rearward ends journal bearings 27 in which are supported the transverse shaft 28. Upon the shaft 28 is rotatably mounted a rocker arm 40 29 connected at its upper end to the eccentric rod 30 to be oscillated by the rotation of the eccentric 25. A ratchet wheel 31 is fixed to the shaft 28, adjacent the rocker arm 29, which is adapted to be engaged by 45 the double direction pawl 32 pivoted on the pin 33 of the rocker arm. Pivoted connected to the stem 34 of the pawl 32 is a rod 35 which is slidable in an aperture of the lug 36 of the rocker arm, and which is sur-

50 rounded by the compression spring 37 which bears at its upper end against the lug 36 and at its lower end against the stem 34 to hold the pawl in contact with the ratchet wheel. By this arrangement, the ratchet 55 wheel 31, and with it the shaft 28, may be caused to rotate in either direction by the oscillation of the rocker arm. Fixed to the shaft 28 to rotate with it, is a sprocket wheel 38 adapted to engage the rack rail 39 60 attached to the cross ties 40 of the mine track. As the rack rail is securely anchored to the cross ties it is evident that the rotation of the ratchet wheel 31 will cause the truck, and with it the coal cutting mechanism, to move along the track, the rate of

rotation of the shaft 28 being such as to give the desired rate of feed to the cutter arm.

A suitable mechanism is provided for preventing retrograde movement of the shaft 28 and the sprocket wheel 38. One form of mechanism for this purpose is shown. It comprises a ratchet wheel 31^a on the end of the shaft 28, and a reversible pawl 34^a mounted on one of the arms 26, and held in position by means of the rod 35^a and the spring 37^a.

When transporting the machine from place to place about the mine, the sprocket wheel 38 must be lifted so as to clear the track rails at switches and crossings. Means 80 for lifting the shaft 28 and sprocket wheel 38 are provided in the hand levers 41 pivoted on the support 42 of the truck platform 1, and connected to the arms 26 by links 43. Guides 44 are provided to confine the hand 85 levers against lateral oscillation, and in these guides are apertures 45 into which may be thrust suitable pins to hold the hand levers in either position desired.

When the machine is to work on the long 90 wall system the working place is prepared by the laying of the track 6 parallel with the coal face and at a suitable distance therefrom, and the rack rail secured in proper working position. Convenient connection is provided with the trackage system of the mine as illustrated at 46 in Fig. 4. The machine is then advanced along the track 6 with the cutter arm 11 extending directly ahead, until the extreme right hand 100 side of the working face is reached. The cutter mechanism is then started and the cutter arm rotated to make the entering or sumping cut. At the same time the truck is advanced by the rack rail mechanism until, 105 when the cutter arm has reached a right angle with the track, the line of the kerf will resemble the dotted line 47 in Fig. 4. When the machine is thus fully sumped the truck will be propelled toward the left hand 110 side of the working face by the rack rail mechanism. After the entire face has been cut, the sprocket wheel 38 will be lifted and the machine proceed to the next place, propelled by the traction of the wheels 4. 115

When using this machine for driving entry the track 6 is laid on the center line of the entry, the rack rail 39 secured in its place and the machine advanced with the cutter arm 11 rotated to the right till its end 120 is in contact with the rib. The truck is then advanced by the rack rail mechanism until the desired depth of cut is effected as in Fig. 6. The cutter arm is then rotated to the left until its end reaches the line of the 125 left hand rib as illustrated in Fig. 7, the machine is then backed out by means of the rack rail mechanism as shown in Fig. 8.

What I claim is:

1. In a system of coal mining apparatus 130

comprising a ground supported track and a portable mechanism adapted to be transported over and remain permanently upon said track and also adapted to cut a horizontal kerf in a coal face while supported on a section of track extending longitudinally toward said face, the combination of a track, a base frame, track wheels supporting the frame, an elongated horizontally projecting cutter arm carried by the base frame and movable laterally across the front thereof, 5
endless chain cutter devices mounted to move in a horizontal path around the periphery of the cutter arm, the arm and cutter devices being adapted to be thrust bodily into and withdrawn bodily from the coal while cutting and while the arm is fixed relatively to the base frame and to be moved laterally while cutting, mechanism 10
carried by the base frame adapted to engage a part of the track structure to positively feed the apparatus bodily toward and away from the coal face to thrust the cutter arm into and withdraw it from the coal 15
as aforesaid, mechanism for swinging the cutter arm laterally, mechanism for driving the track wheels to transport the apparatus bodily over the track, motor devices carried by the base frame, and means for causing 20
the power of the motor devices to actuate the said feeding, swinging and track-wheel-driving mechanisms.

2. In a system of coal mining apparatus comprising a ground supported track and a portable mechanism adapted to be transported over and remain permanently upon said track and also adapted to cut a horizontal kerf in a coal face while supported on a section of track extending longitudinally toward said face, the combination of a track, a base frame, track wheels supporting the frame, an elongated horizontally projecting cutter arm carried by the base frame and movable laterally across the front thereof, 5
endless chain cutter devices mounted to move in a horizontal path around the periphery of the cutter arm, the arm and cutter devices being adapted to be thrust bodily into and withdrawn bodily from the coal while cutting and while the arm is fixed relatively to the base frame and to be moved laterally while cutting, mechanism 10
carried by the base frame adapted to engage a part of the track structure to positively feed the apparatus bodily toward and away from the coal face to thrust the cutter arm into and withdraw it from the coal as aforesaid, mechanism for swinging the cutter arm laterally, motor devices carried by the base frame, and means for causing 15
the power of the motor devices to actuate the said feeding and swinging mechanisms.

3. In a system of coal mining apparatus comprising a ground supported track and a portable mechanism adapted to be trans-

ported over and remain permanently upon said track and also adapted to cut a horizontal kerf in a coal face while supported on a section of track extending longitudinally toward said face, the combination of a track, 5
a base frame, track wheels supporting the frame, an elongated horizontally projecting cutter arm carried by the base frame and movable laterally across the front thereof, endless chain cutter devices mounted to move in a horizontal path around the periphery of the cutter arm, the arm and cutter devices being adapted to be thrust bodily into and withdrawn bodily from the coal 10
while cutting and while the arm is fixed relatively to the base frame and to be moved laterally while cutting, mechanism carried by the base frame adapted to engage a part of the track structure to positively feed the apparatus bodily toward and away from the coal face to thrust the cutter arm into and withdraw it from the coal as aforesaid, mechanism for swinging the cutter arm laterally, mechanism for driving the track wheels to transport the apparatus bodily over the track, manual means carried by the base frame for moving the aforesaid feeding mechanism into and out of engagement with the coöperating part of the track, motor devices carried by the base frame, and manually controllable means for causing the power of the motor devices to actuate the said feeding, swinging and track-wheel-driving mechanisms.

4. In a system of coal mining apparatus comprising a ground supported track and a portable mechanism adapted to be transported over and remain permanently upon said track and also adapted to cut a horizontal kerf in a coal face while supported on a section of track extending longitudinally toward said face, the combination of a track, a base frame, track wheels supporting the frame, an elongated horizontally projecting cutter arm carried by the base frame and movable laterally across the front thereof, endless chain cutter devices mounted to move in a horizontal path around the periphery of the cutter arm, the arm and cutter devices being adapted to be thrust bodily into and withdrawn bodily from the coal while cutting and while the arm is fixed relatively to the base frame and to be moved laterally while cutting, mechanism carried by the base frame adapted to engage a part of the track structure to positively feed the apparatus bodily toward and away from the coal face to thrust the cutter arm into and withdraw it from the coal as aforesaid, mechanism for swinging the cutter arm laterally, manual means carried by the base frame for moving the aforesaid feeding mechanism into and out of engagement with the coöperating part of the track, motor devices carried by the base frame, and manually controllable means for causing the power of the motor devices to actuate the said feeding, swinging and track-wheel-driving mechanisms.

- base frame, and manually controllable means for causing the power of the motor devices to actuate the said feeding and swinging mechanisms.
5. In a system of coal mining apparatus comprising a ground supported track and a portable mechanism adapted to be transported over and remain permanently upon said track and also adapted to cut a horizontal kerf in a coal face while supported on a section of track extending longitudinally toward said face, the combination of a track, a base frame, track wheels supporting the frame, an elongated horizontally projecting cutter arm carried by the base frame and movable laterally across the front thereof, endless chain cutter devices mounted to move in a horizontal path around the periphery of the cutter arm, the arm and cutter devices being adapted to be thrust bodily into and withdrawn bodily from the coal while cutting and while the arm is fixed relatively to the base frame and to be moved laterally while cutting, mechanism carried by the base frame adapted to engage a part of the track structure to positively feed the apparatus bodily toward and away from the coal face to thrust the cutter arm into and withdraw it from the coal as aforesaid, mechanism for swinging the cutter arm laterally, motor devices carried by the base frame, and manually controllable means for causing the power of the motor devices to actuate the said feeding and swinging mechanisms simultaneously and independently of each other, whereby the contour of the kerf can be controlled at will.
6. In a system of coal mining apparatus comprising a ground supported track and a portable mechanism adapted to be transported over and remain permanently upon said track and also adapted to cut a horizontal kerf in a coal face while supported on a section of track extending longitudinally toward said face, the combination of a track, a base frame, track wheels supporting the frame, an elongated horizontally projecting cutter arm carried by the base frame and movable laterally across the front thereof, endless chain cutter devices mounted to move in a horizontal path around the periphery of the cutter arm, the arm and cutter devices being adapted to be thrust bodily into and withdrawn bodily from the coal while cutting and while the arm is fixed relatively to the base frame and to be moved laterally while cutting, a rack-like member secured stationarily external to the base frame, mechanism carried by the base frame adapted to engage the rack-like member to positively feed the apparatus bodily toward and away from the coal face to thrust the cutter arm into and withdraw it from the coal as aforesaid, mechanism for swinging the cutter arm laterally, motor devices carried by the base frame, and means for causing the power of the motor devices to actuate the said feeding and swinging mechanisms.

In testimony whereof, I affix my signature, in presence of two witnesses.

ROBERT R. DUNLOP.
